UNITED STATES PATENT OFFICE.

OTTO MÜLLER, OF BRESLAU, GERMANY, ASSIGNOR TO HANS HAUSER, OF JAGERN-DORF, CZECHOSLOVAKIA.

GUMMING APPARATUS.

Application filed December 29, 1924. Serial No. 758,721.

To all whom it may concern:

Be it known that I, Otto MÜLLER, a citizen of the German Republic, residing at Breslau, Germany, have invented certain new and useful Improvements in Gumming Apparatus, of which the following is a specification.

This invention relates to a gumming apparatus of the type in which the adhesive substance is spread on the surface to be gummed by means of a distributor placed on the reservoir. The improvement according to the invention consists in arranging a valve in a flat tubular piece located in the closing cap and traversing the stopper which closes the orifice of the reservoir. This valve is suspended on one end of a spring the other end of which is attached to a piston guided in said tube and having lateral outlet holes near the point.

The improved gumming apparatus is shown by way of example, on the accompanying drawing in which:—

Fig. 1 shows the reservoir for the adhesive substance in elevation, the front end being shown in section.

Fig. 2 shows in section the reservoir and the distributing device.

Fig. 3 shows in plan view the front end of the reservoir, the closing plate being removed.

Fig. 4 shows in elevation a foot for the reservoir.

The reservoir 15 for the adhesive substance, which is preferably of cylindrical shape is closed at the open front end by a stopper 12 of suitable material which has a central bore. A metal plate 14 tightly fitting in this central bore serves to prevent the outflow of adhesive substance. The stopper 12 is covered by a closing plate 13 of suitable material which has to be removed when the distributing device is to be inserted.

The distributing device consists of a tube 1 closed at the inner end but open at the front end. This tube 1 is fixed in a cap 11 closed at the front end and having an enlarged open rear part which tightly fits on the front end of the reservoir 15. The plate which closes the front end of the cap 11 has a central hole. A hollow piston 4 having a flange at the rear end is located in tube 1 so that its front end projects from said tube.

55 The flange of the piston fits tightly into the

tube 1 so that it is adapted to slide on the inner surface of said tube with slight friction when a pressure is exerted upon the front end or point of the piston 4. The bottom plate of tube 1 has a central hole 7. A spiral spring 2 bearing with the rear end against the bottom plate of tube 1 and with the front end against the flange of piston 4 serves for maintaining the piston in the normal advanced position. In the front end of the tubular piston 4 a spiral spring 3 is attached, on the rear end of which a valve 5 is fixed designed to close the hole 7 in the bottom plate of the tube 1 when the gumming apparatus is in the position for use. On the front end of the piston 4 a ring 9 is fixed which is designed to securely hold the rubber pad 10 which has a large front surface. The front end 6 of the tubular piston has, somewhat behind its point, lateral holes 8.

When the apparatus is not in use the reservoir 15 is inserted in a foot 16 (Fig. 4) so that the front end of the reservoir is pointed upward. The distributing device is not mounted on the reservoir, the front—upper—end of which is covered by plate 13.

To use the gumming apparatus, the cover plate 13 has to be removed and the cap 11 with the tube 1 and the other elements is mounted on the front or upper end of the reservoir 15, the tube 1 which is inserted into the central bore of stopper 12 pushing out the metal plate 14 so that the lower end of this bore is free. The reservoir, after having been taken out of the foot 16 is turned upside down so that the adhesive substance flows from the reservoir 15 into the tube 1 and fills the same. To gum a surface the point of the piston 4 is placed and pressed upon the surface to be gummed. The spring 3 presses then the valve 5 into the hole 7 so that this hole is closed and the inflow of adhesive substance from the reservoir 15 is shut-off. The adhesive substance contained in tube 1 flows out through the holes 8 to be spread by means of the rubber pad 10. As soon as the pressure ceases the piston 4 is brought back to the initial position by the action of spring 3, the valve 5 goes out of hole 7, and the adhesive substance can again flow into the tube 1 from the reservoir 15.

I claim:—

A gumming apparatus comprising in com-

combination a reservoir for the adhesive substance, a stopper closing said reservoir and having a central bore, and a distributing device mounted on said reservoir comprising
5 a cap fitting on the open end of said reservoir, a narrow front end of said cap, a tube open at the front end and having a central hole in its bottom plate centrally mounted in said cap and inserted in the central bore of
10 said reservoir, a tubular piston movably mounted on said tube so that it projects from the front end of said cap and having outflow holes at its front end, a rubber pad on the

front end of said piston for spreading on a surface to be gummed the adhesive substance which flows out from said piston, a spiral spring in said tube for maintaining said piston in the normal forward position, a second spiral spring attached at the front end to said piston, and a valve fixed on the rear end of said second mentioned spiral spring and designed to close the central hole in the bottom plate of said tube when said piston is being pressed in. ¹⁵

In testimony whereof I affix my signature.

OTTO MÜLLER.
